RADIO CONDENSER

Abraham Agronofsky, St. Joseph, Mo.

Application August 3, 1929, Serial No. 333,296
Renewed September 25, 1936

19 Claims. (Cl. 175—41.5)

This invention relates to variable condensers of that type embodying rotary plates interleaving stationary plates, and has for one of its objects to provide a condenser of this character which shall be adapted to enable fine and accurate adjustments and uniform wave length variation to be obtained.

To attain the foregoing and other objects, the nature of which will appear as the description proceeds, the invention comprehends the provision of a condenser wherein the rotary plates shall be mounted in a manner to permit them to be moved through 360° with respect to the stationary plates.

The invention has for a further object to provide a condenser of the character stated wherein the rotary plates shall be mounted for rotation and bodily sliding movement with respect to the stationary plates, whereby to permit them to be moved through 360° with respect to the stationary plates.

The invention has for a still further object to provide a condenser of the character stated wherein the rotary and stationary plates shall be so constructed that the capacity of the condenser will be gradually and uniformly varied during the adjustment of the rotary plates.

The invention is hereinafter fully described and claimed and illustrated in the accompanying drawings, wherein:

Figure 1 is a sectional view taken on a plane extending vertically and longitudinally through the condenser;

Figure 2 is an elevational view illustrating one of the stationary plates and the various positions assumed by the rotary plates during the adjustment of the condenser from minimum to maximum capacity;

Figure 3 is a sectional view taken on the planes indicated by the line 3—3 of Figure 1;

Figure 4 is a sectional view taken on the plane indicated by the line 4—4 of Figure 1;

Figure 5 is a view of some of the rotary plates and the shaft therefor;

Figure 6 is a sectional view taken on the plane indicated by the line 6—6 of Figure 5;

Figure 7 is a sectional view illustrating the manner in which the stationary plates are secured within the frame of the condenser;

Figure 8 is a sectional view taken on the plane indicated by the line 8—8 of Figure 7;

Figure 9 is an elevational view of a fragmentary portion of the rotary plate shifting rack, 55 and

Figure 10 is an elevational view of one of the stationary plates.

The condenser comprises a frame which embodies a front plate 1, a rear plate 2 and spacing rods 3, which parts are secured together by machine screws 4. A plate 5 is arranged in front of and spaced from the frame, and it is secured to the frame by bars 6 of bakelite or other insulating material.

The bars 6 extend transversely across the frame, and are arranged within the recesses 7 formed in the frame plates 1 and 2. One of the bars 6 is arranged at the corner of the frame, another of the bars is arranged at the end of the frame remote from such corner, and the remaining bar is arranged at the bottom of the frame.

Stationary or stator plates 8 are arranged within the frame, and are held therein and maintained in relatively spaced relation by strips 9 of bakelite or other insulating material. The strips 9 are secured to the bars 6 and are provided with notches 10 for the reception of portions of the edges of the stator plates 8. The stator plates 8 are provided with notches 11 for the reception of the strips 9. The side walls of the notches 10 contact with the sides of the stator plates 8, and the end walls of the notches 11 contact with the sides of the strips 9, with the result that the stator plates are positively held against relative movement.

The stator plates 8 are of elongated formation and are provided with slots 12 of such formation as to separate the plates into substantially circular portions 13 and substantially scroll portions 14. The circular portions 13 and the scroll portions 14 of the respective stator plates 8 are arranged in alignment, and the ends of the scroll portions 14 are connected to opposite edges of the circular portions 13. The scroll portions 14 extend longitudinally from the circular portions 13, they then extend upwardly to points above the circular portions 13, and thereafter they extend in the direction of the circular portions 13.

The scroll portions 14 gradually increase in area from the lower edges of the circular portions 13 to points close to the upper edges of the circular portions 13, and then they gradually decrease in area from such points to the upper edges of the circular portions 13.

The frame plates 1 and 2 are provided with inclined slots 15, which register with the slots 12 of the stator plates 8. Bearing strips 16 of bakelite or other insulating material are ar-

ranged within the slots 15 and are secured against the upper walls thereof by machine screws 11. Rack bars 18 of bakelite or other insulating material are secured to the inner or opposing sides 5 of the frame plates 1 and 2 by machine screws 19. The rack bars 18 are arranged below the slots 15 with their teeth uppermost. Pinions 20 rest upon and mesh with the rack bars 18, and are secured to bearing sleeves 21 and 22. The 10 bearing sleeves 21 and 22 pass through the slots 15 and the frame plates 1 and 2 and are maintained out of contact with the bottom walls of the slots and in contact with the lower sides of the bearing strips 16 by the pinions 20. The 15 bearing sleeves 21 and 22 carry the shaft 23 for the rotary or rotor plates 24, and are screw threadedly engaged with the reduced ends 25 of the shaft. The bearing sleeves 21 and 22 are secured to the shaft by lock nuts 26. The pinions 20 contact with the shoulders 27 formed by the reduction of the ends of the shaft 23, one of the pinions contacts with the inner side of the bearing strip 16 carried by the frame plate 1, and the other pinion contacts with an annular 25 flange 28, which is formed on the bearing sleeve 21 and contacts with the inner side of the bearing strip 16 carried by the frame plate 2, whereby to hold the shaft against accidental endwise movement with respect to the stator plates 8. 30 The rotor plates 24 are of circular formation, and are provided adjacent their edges with notches 29, which together with notches 30, formed in opposite sides of the shaft 23, permit an interlocking connection between the rotor plates and shaft. The walls of the notches 29 and 30 contact so as to positively hold the stator plates 24 against accidental movement with relation to each other and to the shaft 23. The 35 rotor plates 24 extend in a common direction from the shaft 23 and are interleaved with the stator plates 8.

As the ends of the shaft 23 are arranged in slots, it and the rotor plates 24 are mounted for bodily sliding movement with respect to the 40 stator plates 8, and as the pinions 20 are fixed to the shaft and engage the fixed rack bars 18, the shaft and the rotor plates will be turned or rotated during their sliding movement. Means are provided for imparting these sliding and 45 rotating movements to the shaft 23 and the rotor plates 24, and it is adapted to be operated by a knob arranged on the dial of the radio set equipped with the condenser.

This means comprises a rack bar 31, which is 50 slidably mounted upon a supporting strip 32 of bakelite or other insulating material. The supporting strip 32 is secured to the outer side of the frame plate 1 by machine screws 33, and it is arranged below the slot 15 of this frame plate. 55 The rack bar 31 is provided at one end with an upstanding lug 34, which receives the bearing sleeve 22 and is retained thereon by the lock nut 26. A spindle 35 is journaled in a bearing sleeve 36 carried by the plate 5. The bearing sleeve extends through the plate 5 and is secured 60 in place by flanges 37 carried thereby and contacting with the inner and outer sides of the frame.

The spindle 35 is provided at its inner end 70 with a pinion 38, which meshes with the rack bar 31. The spindle 35 is long enough to extend through the panel of the instrument in connection with which the condenser is used, and the condenser is secured to the panel by the bearing 75 sleeve 36, which extends through the panel.

The bearing sleeve is in turn secured to the panel by its outer flange 37 and a nut 39 arranged thereon, the flange and nut contacting with opposite surfaces of the panel. The shaft 35 is held against inner endwise movement in the 5 bearing sleeve 36 by a spring 40, which is secured at one end by a screw 41 to the plate 5 and which has its other or free end arranged in contact with the inner end of the spindle. The spindle 35 is provided at its outer end with a dial 42 10 and a knob 43.

It should be apparent from the foregoing description, taken in connection with the accompanying drawings, that the rotation of the knob 43 will impart a sliding movement to the rack 15 bar 31, that the movement of the rack bar will bodily slide the rotor plates 24 diagonally across the stator plates 8, and that the rotor plates will, during their sliding movement, be rotated 20 through 360° by the rack bars 18 and pinions 20. As the rotor plates 24 are supported at their edges, they will, during their downward and 25 rotary sliding movements, pass gradually increasing areas of the stator plates 8, and they will, during their upward sliding and rotary movements pass gradually decreasing areas of the stator plates, with the result that fine and accurate 30 adjustments and uniform wave length variation may be obtained.

The circular portions 13 of the stator plates 8 30 and the rotor plates 24 are of the same diameter, and said circular portions are provided with notches 44 for the reception of the shaft 23, so as to permit the rotor plates to be adjusted into 35 fully opposed relation with respect to said circular portions.

While I have described the principle of the invention together with the structure which I now consider the preferred embodiment thereof, it is 40 to be understood that the structure shown is merely illustrative and that such changes may be made, when desired, as fall within the scope of the invention as claimed.

I claim:—

1. A condenser comprising stator plates provided with circular and scroll portions, rotor plates, and means supporting the rotor plates for movement past said portions of the stator plates. 45

2. A condenser comprising stator plates provided with slots, rack bars extending across the 50 slots, a shaft extending through the slots, pinions fixed to the shaft and engaging the rack bars, rotor plates carried by the shaft, and means for imparting movement to the shaft.

3. A condenser comprising stator plates provided with slots, rack bars extending across the 55 slots, a shaft passing through the slots, pinions fixed to the shaft and meshing with the rack bars, rotor plates secured to the shaft, a slidably mounted rack bar provided with a lug engaging the shaft, an operating spindle, and a pinion carried by the spindle and engaging said last rack bar.

4. A condenser comprising frame plates provided with inclined slots, bearing strips secured 65 within the slots and spaced from the bottom walls thereof, rack bars secured to the plates below the slots, bearing sleeves contacting with the under side of the bearing strips, pinions fixed to the bearing sleeves and engaging the rack bars, stator 70 plates secured within the frame and provided with slots intersected by the slots of the plates, a shaft extending through all of said slots and having its ends fixed in the bearing sleeves, rotor plates fixed to the shaft, a slide fixed to one of the plates 75

below the slot therein, a rack bar mounted upon the slide and provided with a lug engaging one of the bearing sleeves, a spindle, and a pinion carried by the sleeve and meshing with said last 5 rack bar.

5. A condenser comprising a stator having one portion of relatively large width, a second portion of relatively small width connected to said first portion and extending in a direction away from 10 said large portion and a third portion of intermediate width gradually increasing in width from said second portion and extending in the direction of said first portion whereby to provide a substantially closed loop, a movable plate, means for 15 mounting said plate for rotary movement in a plane parallel to said stator, and means for bodily shifting the axis of the plate for inductive engagement by the plate with selected portions of said stator said plate being rotatable relative to 20 the selected portion of the stator.

6. A condenser comprising an elongated stator having a relatively large portion, a second relatively small portion secured to said large portion and extending in a direction away therefrom, a 25 third portion of a size intermediate said first and second portions and extending in the direction of said first portion, said third portion being of tapering construction adjacent the connection thereof with the first portion, a rotor plate, and means for mounting said rotor plate for swingable and bodily shiftable movement to selected 30 portions of said stator.

7. A condenser comprising stator plates and 35 rotor plates, said rotor plates being mounted for rotation through an arc of more than 180 degrees about an axis shiftable in a direction perpendicular to said axis, and means for simultaneously rotating said plates and shifting said axis, said 40 rotor plates having an increasing area thereof in capacity relation to said stator plates throughout their arc of rotation in one direction and a decreasing area thereof in capacity relation to said stator plates throughout their arc of rotation in the opposite direction.

45 8. A condenser comprising stator plates and rotor plates, means for mounting said rotor plates for rotation through an arc of approximately 360 degrees and means for simultaneously rotating and shifting the axis of rotation of said plates 50 in a direction perpendicular to said axis, said rotor plates having an increasing area thereof in capacity relation to said stator plates throughout their arc of rotation in one direction and a decreasing area thereof in capacity relation to said 55 stator plates throughout their arc of rotation in the opposite direction.

9. A condenser comprising stator plates and 60 rotor plates, said rotor plates being mounted for rotation through an arc of approximately 360 degrees about an axis shiftable in a straight line perpendicular to said axis, and means for simultaneously rotating said plates and shifting said axis, said rotor plates having an increasing area thereof in capacity relation to said stator plates 65 throughout their arc of rotation in one direction and a decreasing area thereof in capacity relation to said stator plates throughout their arc of rotation in the opposite direction.

10. A condenser comprising stator plates and 70 rotor plates, said rotor plates being mounted for rotation through an arc of more than 180 degrees about an axis shiftable in a direction perpendicular to said axis, and means for simultaneously rotating said plates and shifting said 75 axis, said rotor plates and stator plates being of

such relative shapes that said rotor plates move into juxtaposition with progressively increasing areas of said stator plates throughout a movement through an arc of more than 180 degrees during rotation in one direction and with progressively decreasing areas of said stator plates during a rotation through an arc of more than 180 degrees in the opposite direction. 5

11. A condenser comprising stator plates and rotor plates, means for mounting said rotor plates 10 for rotation through an arc of approximately 360 degrees and means for shifting the axis of rotation of said plates in a direction perpendicular to said axis simultaneously with rotation thereof, said rotor plates and stator plates being of such 15 relative shapes that said rotor plates move into juxtaposition with progressively increasing areas of said stator plates throughout their rotation through approximately 360 degrees in one direction and with progressively decreasing areas of 20 said stator plates during their rotation through approximately 360 degrees in the opposite direction.

12. A condenser comprising stator plates and rotor plates, said rotor plates being mounted for 25 rotation through an arc of approximately 360 degrees about an axis shiftable in a straight line perpendicular to said axis, and means for simultaneously rotating said plates and shifting said axis, said rotor plates and stator plates being of 30 such relative shapes that said rotor plates move into juxtaposition with progressively increasing areas of said stator plates throughout their rotation through approximately 360 degrees in one direction and with progressively decreasing areas 35 of said stator plates during their rotation through approximately 360 degrees in the opposite direction.

13. A condenser comprising a stator having one portion thereof of relatively large size, a second portion of relatively small size connected therewith by a narrow connecting portion, and an intermediate portion connected to said second portion and to said first portion at a point remote from the narrow connecting portion joining said second and first portions, a movable plate, means for mounting said plate for rotary movement in a plane parallel to said stator, and means for bodily shifting the axis of the plate to move the plate into inductive relation with selected 40 portions of the stator. 45

14. A condenser comprising stator plates and rotor plates, a rotatable member carrying said rotor plates, means for rotating said rotatable member through an arc of more than 180 degrees 50 and simultaneously shifting said rotatable member transversely of its axis and a rotatable member for operating said means, said rotor plates having an increasing area thereof in capacity relation to said stator plates throughout their arc of rotation in one direction and a decreasing area thereof in capacity relation to said 55 stator plates throughout their arc of rotation in the opposite direction.

15. A condenser comprising a rotatable shaft, 60 rotor plates fixed on said shaft, stator plates co-operating therewith, a rotatable actuating member, means for moving said shaft transversely of its axis of rotation by rotation of said actuating member and for simultaneously rotating said 65 shaft through an arc of more than 180 degrees during movement of said shaft transversely of its axis, said rotor plates having an increasing area thereof in capacity relation to said stator plates throughout their arc of rotation in one 70 75

- direction and a decreasing area thereof in capacity relation to said stator plates throughout their arc of rotation in the opposite direction.
16. A condenser comprising a rotatable shaft, 5 rotor plates fixed on said shaft, stator plates co-operating therewith, a rotatable actuating member, means for moving said shaft transversely of its axis of rotation by rotation of said actuating member and for simultaneously rotating said 10 shaft through an arc of more than 180 degrees during movement of said shaft transversely of its axis, said stator members and said rotor members being related to each other so that the areas of said rotor members juxtaposed to said 15 stator members vary continuously progressively during the movement of said rotor members about and with said shaft through an arc of more than 180 degrees in one direction of rotation.
17. A condenser comprising a rotatable shaft, 20 rotor plates fixed on said shaft, stator plates co-operating therewith, a rotatable actuating member, means for moving said shaft transversely of its axis of rotation upon rotation of said actuating member through a distance proportional to the rotation of said actuating member, and means for rotating said shaft through an arc proportional to the transverse movement of said shaft upon such movement of said shaft, said shaft 25 being rotatable through an arc of substantially 360 degrees to rotate said rotor plates about said axis through an arc of substantially 360 degrees, 30 said stator members and said rotor members being related to each other so that the areas of said rotor members juxtaposed to said stator members vary continuously during the movement of said rotor members about and with said shaft.

18. A condenser comprising a rotatable shaft, 5 rotor plates fixed on said shaft, stator plates co-operating therewith, a rotatable actuating member, means for moving said shaft transversely of its axis of rotation upon rotation of said actuating member through a distance proportional to the rotation of said actuating member, and means for rotating said shaft through an arc proportional to the transverse movement of said shaft upon such movement of said shaft, said shaft 10 being rotatable through an arc of substantially 360 degrees to rotate said rotor plates about said axis through an arc of substantially 360 degrees, 15 said stator members and said rotor members being related to each other so that the areas of said rotor members juxtaposed to said stator members vary continuously during the movement of said rotor members about and with said shaft.

19. A condenser comprising a stator plate, 20 a rotor plate, a shaft for the rotor plate, and means for bodily shifting the shaft and rotor plate transversely of the axis of rotation thereof, and simultaneously produce rotation thereof, to provide swinging movement of the rotor plate through an arc of substantially 360 degrees, 25 said rotor having an increasing area thereof in inductive relation to said stator plate throughout its arcuate movement in one direction and and a decreasing area thereof in inductive relation to said stator plate throughout its arcuate movement in the opposite direction.

ABRAHAM AGRONOFSKY.
